UNITED STATES PATENT OFFICE.

HERBERT SAMUEL ELWORTHY, OF LONDON, ENGLAND.

APPARATUS FOR COLLECTING CARBONIC-ACID GAS.

SPECIFICATION forming part of Letters Patent No. 619,398, dated February 14, 1899.

Application filed December 22, 1897. Serial No. 663,050. (No model.)

To all whom it may concern:

Be it known that I, HERBERT SAMUEL ELWORTHY, a subject of the Queen of Great Britain, residing at London, in the county of 5 Middlesex, England, have invented certain new and useful Improvements in Apparatus for Collecting Carbonic-Acid Gas from a Closed Vat or Tun; and I do declare the following to be a full, clear, and exact description of the invention, such as will enable others skilled in the art to which it appertains to make use of the same.

The invention relates to apparatus for collecting carbonic-acid gas from a closed vat or 15 tun; and it consists in the novel construction and combination of the parts of the apparatus hereinafter described and claimed.

I have heretofore obtained foreign patents in the following countries, viz: England, No. 22,248 of 1891; France, No. 224,808, dated 20 August 10, 1892, and India, No. 68 of 1892.

The accompanying drawings are in illustration of the invention.

Where closed vats are used, I collect the gas 25 under low pressure—say two or three inches water-pressure—by means of the following device, as illustrated in Figure 1:

The vat being hermetically closed by means 30 of a cover, a screw-down lid, or other device at *a* a small bellows-shaped apparatus *b* is placed on and fastened air-tight to the cover *a* of the vat, but communicating with the interior by means of a small hole. To the top 35 of the bellows a rod or wire *c* is attached and passes down through the hole in the cover of the vat, being fastened at its lower end to one arm of a lever *d*, the other end of which carries a valve *e*, which is held in its place by means of a spring *f*, or the lever may be 40 loaded with an adjustable weight. When the gas in the vat attains a certain pressure regulated by means of the spring *g* or weight, the gas passing up through the hole in the cover expands the bellows *b* and, lifting the 45 lever *d*, opens the valve *e* at the other end and allows the gas to escape, closing it again as the pressure falls. Over the valve *e* is placed an outlet-pipe *g*, leading to any simple form of low-pressure air-pump or double- 50 action bellows or to a gas-holder, the pump drawing the gas from the vat or from the gas-

holder and passing it through the purifying apparatus.

For collecting the carbonic-acid gas from open fermenting vats or tuns the following 55 device may be used:

A cover is provided made of any suitable material—such, for instance, as galvanized, buckled, or corrugated steel or iron plates—of a rather larger diameter than the top of 60 the vat and having a deep flange or rim. Around the outside of the vat and a little below the top is fixed a deep narrow annular channel, into which the rim or flange of the cover fits loosely. This channel is partially 65 filled with any suitable liquid—such as water, mercury, &c.—which acts as a lute or seal to prevent the escape of carbonic-acid gas and also the entrance of air into the vat, except under excessive pressures. The au- 70 tomatic regulator as described and illustrated above for closed vats may be attached to this cover, so as to collect the gas at any required pressure. This regulator being so arranged as to close automatically when the pressure 75 in the vat falls below a certain fixed amount, no atmospheric air can enter the vat.

In order to reduce the number of covers required for a given number of vats or tuns, the covers may be suspended by means of pulleys, 80 blocks, and rollers or other suitable means to an overhead rail, whereby they can be transferred from one vat to another, as required.

The purifying apparatus is arranged as follows: The gas is passed through a siphon 85 gas-trap (such as those illustrated in Figs. 2 and 3) and thence, first, to a vertical cylinder fitted with an inlet-pipe for the gas and an outlet-pipe at the top and having also a device for sprinkling water, which may be 90 caused to revolve by the issuing gas or by an external motor in the usual well-known way, and the cylinder is also fitted with charging and discharging manholes. This cylinder may be filled with any suitable material— 95 such as coke, charcoal, pumice-stone, flints, &c.—over which the water from the sprinkler is caused to flow slowly and continuously. The carbonic-acid gas being forced in at the bottom and passing upward is brought continually in contact with fresh water, whereby 100 all the soluble impurities—such as alcohol,

acetic ether, &c.—are removed. The gas after passing through this scrubber is passed, second, through a second scrubber similar to the first and fitted similarly, but through 5 which a melted fat or oil, preferably mineral oil, or a liquid hydrocarbon—such, for instance, as melted paraffin, wax, or vaseline—as free as possible from odor and taste is made to flow instead of water. The gas passing upward 10 through interstices of the coke or other material is brought into intimate contact with the oil or other substance, which, having a great affinity for the ethers, removes them from the gas. These ethers may be recovered 15 from the fat or oil or hydrocarbon and utilized for the manufacture of fruit essences or other suitable processes and the oil purified by distilling them off, preferably with steam, superheated, if necessary. The alcohol may also 20 be recovered from the first wash-water by any suitable means of the well-known kind. The carbonic-acid gas after passing through the two scrubbers above mentioned and containing now only mere traces of impurities and a 25 certain amount of moisture is passed through a desiccator containing any suitable material—such as dry carbonate of potash, chlorid of calcium, sulfuric acid, or materials soaked in sulfuric acid, &c., but preferably 30 carbonate of potash or chlorid of calcium. The desiccator consists of a vessel containing a number of shelves, preferably movable, over which the gas is compelled to flow, the desiccating material being placed on these shelves, 35 and the gas in passing over loses its moisture and escapes at the upper end nearly or quite dry. If preferred, two or more desiccating materials may be used either in separate vessels or on different shelves of the same vessel. These desiccating materials may also 40 be recovered and used over again by driving off moisture either by direct fire or by passing a current of hot dry air over them. The latter process may be performed without 45 removal of the substance from the desiccator. The dry carbonic-acid gas is now passed through a series of tubes or pipes, preferably cast-iron, arranged in a furnace and heated red-hot. The first of these tubes may contain 50 coke, or metallic copper, or iron, or zinc, preferably in the form of turnings, to remove any traces of oxygen which the gas may contain. The other tubes contain oxid of copper or other easily-reducible oxid. I prefer 55 to use, however, oxid of copper formed in the following manner: All the tubes except the first being closely filled with copper-turnings are heated to a red heat and a current of air is passed through them, whereby a coating 60 of oxid is formed on the surface of the turnings, which oxid may be renewed in the same way whenever it has become reduced. Copper wire or copper nails may be substituted for the copper-turnings, or the ordinary commercial 65 black oxid of copper may be used, or the oxid of copper may be formed in the pores and on the surface of a porous or fibrous material—such

as fire-brick, pumice-stone, asbestos, or the like—by saturating the material with a solution of nitrate of copper or a solution of an inorganic salt of copper, such as the acetate, and then drying and finally decomposing the copper salt at a high temperature in the presence of air, the treatment being repeated, if necessary. Other chemical substances—such as chromate of lead, bichromate of potash or soda, binoxid of manganese, or other substance which at a high temperature parts with its oxygen in the presence of organic matter—may be substituted for the oxid of copper. 75 When the carbonic-acid gas is brought into contact with the hot oxid of copper by being passed through the tubes containing it, all the remaining impurities are removed, being for the most part converted into carbonic-acid 80 gas and water. The remaining impurities are removed for the purpose of obtaining a pure gas. The impurities generally present consist of ethers and alcohols of a higher boiling-point than ordinary ethylic alcohol, and their removal is effected by their combination in contact with metallic oxid for the above-mentioned purpose of obtaining a pure carbonic-acid gas. Should sensible traces of oxygen be found resulting from the decomposition of 95 organic compounds containing this gas, it may be completely removed by placing a small amount of metallic copper in the shape of turnings, wire-gauze, or nails in the last tube. When the oxid of copper described is reduced 100 by the action of the organic matter contained in the impure carbonic-acid gas, it may be completely regenerated by passing air over it, and the resulting hot air may be utilized for redrying the desiccating material. The 105 carbonic-acid gas, now perfectly purified, may be cooled in an ordinary condenser and compressed or liquefied by any suitable compressor and placed in iron or steel bottles or other suitable holders for sale or use. 110

In large vats, such as are used by brewers, instead of a wooden or metallic cover the vats may be protected against contamination by atmospheric air by covering them with a waterproof or oiled-canvas sheet, the edges of 115 which are secured to the vat in any convenient manner.

The gas may be run from the fermenting-vats into a counterbalanced gas-holder of the usual kind, which itself acts as a regulator 120 without intermediate gas-traps or regulating-valves. Where the vats are at a higher level than the gas-holder, the carbonic-acid gas generated may be siphoned off into the gas-holder, great care being taken to prevent any 125 air from being mixed with the gas withdrawn from the vats.

Figs. 2 and 3 represent two forms of gas-traps, (where such are used,) the pressure being regulated by the level of the water in the 130 trap. The baffle-plates *h* shown in Fig. 3 tend to dry the escaping gas, and similar plates may also be used in the apparatus shown in Fig. 2.

Having now particularly described and as-

certained the nature of my said invention and in what manner the same is to be performed, I declare that what I claim is—

The herein-described apparatus for collecting carbonic-acid gas from a closed vat or tun, the automatic apparatus consisting of the bellows *b* secured air-tight to the cover *a* of the closed vat or tun and communicating with said vat or tun through a small hole, a rod *c* attached at its upper end to the top of the bellows *b* and passed down through the hole in said cover, and fastened at its lower end to one end of the lever *d* fulcrumed to the under side of the cover and connected at its

other end with a valve *e* seated in the lower end of the vertical pipe *g*, and the spring *f* connected at its lower end to the lever *d* between its fulcrum and its connection with the valve *e*, and the thumb-nut on the upper face of the head of the tun or vat connected with the spring *f* to regulate the tension of said spring, substantially as set forth.

In testimony whereof I hereunto affix my signature in presence of two witnesses.

HERBERT SAMUEL ELWORTHY.
